UNITED STATES PATENT OFFICE.

SARAH A. GRAHAM, OF MARION, IOWA.

DESIGN FOR A LINE-WIRE INSULATOR.

SPECIFICATION forming part of Design No. 27,756, dated October 19, 1897.

Application filed August 11, 1897. Serial No. 647,924. Term of patent 14 years.

To all whom it may concern:

Be it known that I, SARAH A. GRAHAM, a citizen of the United States, residing at Marion, county of Linn, and State of Iowa, have 5 invented and produced a new, original, and useful shape for Line-Wire Insulators, which is fully set forth in the following specification, reference being had to the accompanying drawings, forming a part thereof.

10 This design relates to glass or other insulators for electric line-wires.

In the drawings, Figures 1 and 2 are elevations in planes at right angles to each other, Fig. 1 showing the insulator viewed in the 15 direction of the run of the wire at the side at which the wire is entered. Fig. 3 is a view in section at the plane 3 3 on Fig. 1.

In design this insulator A is exteriorly approximately cylindrical, being slightly tapered longitudinally. It has non-distinctive 20 and non-essential features—to wit, an interiorly-threaded cavity A', extending into the lower end, and the annular superficial groove A². Its characteristic and essential features

are a lateral notch or slot A³, extending from 25 one side substantially to the center, and the shoulder A⁴, curved in vertical plane and located at the inner end of the lateral slot A³ and somewhat below the level of the mouth of the slot. This lower level is reached by a 30 downward extension A⁵⁰ of the slot A³ at its inner end.

I claim—

The design for an electric-line-wire insulator herein shown and described, which is 35 exteriorly approximately cylindrical, and is characterized by the lateral slot A and the vertically-curved shoulder A⁴, located at the inner end of the slot and below the level of its outer end. 40

In testimony whereof I have hereunto set my hand, in the presence of two witnesses, at Marion, Linn county, Iowa, this 30th day of July, 1897.

SARAH A. GRAHAM.
